UNITED STATES PATENT OFFICE

WILLIAM H. MCKINNEY, JR., OF MEMPHIS, TENNESSEE, ASSIGNOR TO COTTON BUCKLE & TAG CO., INC., A CORPORATION OF TENNESSEE

BUCKLE

Application filed November 12, 1926. Serial No. 147,996.

This invention relates to buckles and more particularly to a bale tie buckle.

The bale tie buckles, especially those used on high density bales, are subjected to great strain. It has been the practice to form buckles, for this purpose, of a single piece of metal. This is generally made of rectilinear shape formed from heavy gauge wire. A characteristic feature of prior constructions is the smoothness of that portion of the buckle which contacts with the bale band. This structure presents the least possible resistance to the tendency of the tension band to spread the buckle and of consequence disadvantage, that is to say to prevent the deformation of the buckle due to the stress exerted by the band, it has been proposed to form the buckle with hooked ends which engage each other and form, in effect, a positive lock. A disadvantage inhering in this type of buckle is that it requires a metal of not inconsiderable resiliency in order that the ends may spring apart and the hooks disengage when pressure on the buckle is relieved. In addition, this type of buckle requires the use of more material.

It is an object of this invention to provide a buckle which resists the tendency to spread under stress.

Another object is to prevent the spreading of the buckle by a means incorporated in the buckle itself.

A further object is to provide a method of forming a bale buckle to produce a structure which resists the tendency of the buckle to deform under stress.

An additional object is to provide a deformation resisting means for a buckle without increasing the material used.

Yet another object is to devise a method for resisting deformation of buckles which is applicable to existing types.

I accomplish these and other important objects by the provision of an anti-spread means which may be applied to the band engaging portion of a buckle.

In order that this invention may be more readily understood, structural embodiments are disclosed in detail in the accompanying

drawings. In these the same numbers represent identical elements throughout the several views, of which,

Figure 1 is a perspective view of the bale buckle;

Fig. 2 is a partial plan view of the buckle shown in Fig. 1;

Fig. 3 is a sectional view on the line 3-3 of Fig. 2;

Figs. 4, 5, 6 and 7 are views of modifications of the device shown in Fig. 1.

Fig. 8 is a plan view of the buckle with the ends of the bale bands attached thereto.

In Fig. 1 there is shown a bale buckle made from a single piece of heavy gauge wire. This comprises essentially the top 1, side bars 2 and the end bars 3. As shown, particularly in Figs. 2 and 4, the end bars extend from the side bars so that the respective free ends 4 and 5 are initially laterally spaced and extend, the one past the other, in overlapping relation. The end of each of these bars is formed with a beveled surface 6.

The operation of the structure thus far described will be apparent. One looped end of the bale band is adapted to register flatly with the upper end 1 of the buckle. When it is desired to lock the band on the bale, the loop on the other end of the band is passed through the gap between the juxtaposed ends 4 and 5 and twisted slightly. If the pressure on the bale is now released, it will expand.

As the bale expands, pressure is exerted on the buckle. Initially the spaced ends 4 and 5 are constrained to approach each other due to the lateral components of thrust exerted by the band. When the initially spaced portions abut, the expansive force of the bale in effect acts to spread the buckle. When the band engaging faces of the end bars 3 and 4 are smooth, as in prior constructions, the only resistance offered to the distorting force of the band is the inherent tensile strength of the metal buckle. I have found that by providing these band engaging portions with frictional surfaces, the tendency of the band to spread the buckle is greatly minimized.

By treating these surfaces of the buckle so that a plurality of corrugations, or points, or in fact any generally roughened surface is

provided, this desirable result may be attained.

The buckles may be treated in a number of ways to provide the requisite frictional contact surface. As is shown in Figs. 1 to 3, the end bars 3 may be formed with alternating grooves 7 and lands 8. The projecting lands in effect present a plurality of frictional points and thereby greatly increase the friction between the bars and band. The grooves 7 may extend only across the top of the end bars. I intend, however, to have the grooves extend some distance down the flanks of the side bars so that the loop of the band engages tightly with the bar throughout a large portion of its surface. It will be understood that the grooves may be stamped out, filed, cut in, or formed in any desirable or convenient manner.

An increased frictional contact between the band and buckle may be insured by other means. Thus, as shown in Fig. 4, a series of lateral grooves 9 and longitudinal grooves 10 may be cut, or otherwise formed in the band engaging portions of the buckle to provide a reticulated structure. This insures an increased frictional contact between the band and buckle and is thus well calculated to effectuate the underlying principle of the invention.

In Fig. 5 I have shown another structure designed to accomplish the function performed by the devices hereinbefore described. Thus the band engaging portions of the buckle may be provided with a number of pyramidal protrusions 11. These may be obtained by any suitable method, as by stamping with a properly shaped die or by cutting into the material with a saw or file. A peculiar advantage accrues from the use of this particular type of surface inasmuch as it provides a plurality of relatively pointed surfaces. This increases the friction between the band and buckle and more nearly approaches a positive locking contact. As in the other modifications, the tapered protuberances may extend well down the side of the bars to thereby engage a large portion of the end loop of the band.

Another modification which embodies the broad concept of this invention is shown in Fig. 6. In the device disclosed by this figure, the short end bars are formed with longitudinal grooves 12 which extend transversely to the horizontal and vertical planes of the bars. These grooves are preferably angular in cross section rather than channel shaped as the grooves of the device shown in Fig. 1. I prefer to form the grooves of substantially V-shape for the reason that these are effective and are easily formed in the bar. By reason of this structure, the band engaging portions of the bars are more pointed and hence insure a more effective contact with the band.

In Fig. 7 there is depicted another arrangement of the frictional surface. This comprises a plurality of indentations or depressions 14 and the adjacent and alternate projections 15. In this modification the depressions on each side of the central vertical plane of the end bars 3 are angularly disposed. I prefer to position the grooves so that those on one of the short legs are not in parallel relation to those on the other. The grooves then diverge from the central longitudinal plane of the short legs, and extend rearwardly away from the free ends 4 and 5.

The operation of the several modifications will be apparent from the foregoing description. One loop end of the band is inserted in the buckle, through the opening in the end bars, and then drawn up against the upper end bar 1. The loop on the other end of the band is inserted between the free ends 4 and 5. As the compressor is released, the bale expands and the then tensioned band exerts a stress on the buckle. The tendency of the buckle to spread under this stress is restricted by the provision of greater friction resistance resulting from the corrugated band engaging surfaces of the buckle.

The principle of providing for a greater frictional resistance to the spread of the buckle under stress has been illustrated in a buckle having initially spaced overlapping end portions. It will be readily appreciated, however, that this is merely a typical embodiment. I conceive the invention as residing broadly in the idea of so forming the band engaging surfaces that distortion of the buckle is minimized. Hence the principle may be applied to any type of buckle having an opening which forms an entering means for a band, whether or not the ends overlap, abut or positively lock. Since the inventive concept admits of many specific mechanical embodiments, I do not intend to be restricted to any particular structure except as such limitations are imposed by the appended claims.

I claim:

1. A bale buckle comprising a top bar, side bars and spaced end bars, and means coacting with a bale band to restrain spread of the buckle under stress.
2. A bale buckle comprising a single piece of material bent in polygonal shape to present a top bar, side bars, and spaced end bars, the end bars being provided with means to restrict spread of the buckle when placed under stress.
3. A buckle comprising a single piece of metal forming a top bar, side bars and spaced band engaging end bars, said end bars being formed with lateral corrugations.
4. A buckle comprising integral top bar, side bars and spaced end bars, the end bars being provided with a plurality of protrusions arranged to prevent lateral spread of said end bars under stress.

5. A bale buckle comprising integrally formed top, side and spaced end bars, the end bars being laterally grooved for a greater portion of their surfaces.
- 5 6. A bale buckle comprising integral top and side bars and laterally grooved end bars extending from the side bars into initially spaced relation.
- 10 7. A bale buckle comprising integral top and side bars, laterally grooved end bars extending from the side bars into initially spaced and overlapping relation.
- 15 8. A bale buckle comprising integral top and side bars, laterally grooved end bars extending from the side bars into initially laterally spaced and overlapping relation.
- 20 9. A bale buckle comprising a top bar, side bars and spaced end bars, and means on the end bars to restrain spread of the buckle under stress and to prevent slippage of the band.
- 25 10. A buckle comprising a single piece of metal forming a top bar, side bars and spaced band engaging end bars and a plurality of lateral corrugations on said end bars.
- 30 11. A buckle comprising integral top, side, and spaced end bars, the end bars being formed with lateral grooves as and for the purpose described.
- 35 12. A bale buckle comprising integral top, side, and spaced end bars, the end bars being provided with a plurality of obliquely disposed projections on the band engaging surfaces of each end bar.
- 40 13. A bale buckle comprising integral top, side, and spaced end bars having a plurality of obliquely disposed V-shaped projections formed on band engaging surfaces of said end bars.
- 45 14. A bale buckle comprising integral top, side, and spaced end bars, the band-engaging portions of the end bars being formed with angularly disposed V-shaped projections.
- 50 15. A bale buckle of polygonal shape comprising a single piece of metal bent to provide a top bar, a plurality of side bars and end bars, said side bars being spaced to embrace a bale band, and said end bars having surfaces roughened in such a manner as to prevent lateral spread under stress.
- 55 16. A bale buckle comprising a top bar, side bars, spaced end bars and means for increasing the coefficient of friction between the bale band and said end bars, said means acting in such a manner as to prevent lateral spread of said end bars under stress.

In testimony whereof I affix my signature.
WILLIAM H. McKINNEY, JR.
